UNITED STATES PATENT OFFICE.

ORLANDO A. LEMON, OF YORK, NEBRASKA.

AUTOMATIC HOG-OILING DEVICE.

Application filed February 29, 1924. Serial No. 696,022.

To all whom it may concern:

Be it known that ORLANDO A. LEMON, a citizen of the United States, residing at York, in the county of York and State of Nebraska, has invented certain new and useful Improvements in Automatic Hog-Oiling Devices, of which the following is a specification.

This invention relates to an automatic hog 10 oiling device and has for its principal object to provide a simple and efficient means for automatically spraying the hog with an insecticide or disinfectant as the hog passes through the device.

15 A further object of the invention is to provide an automatic hog oiling device which is adapted to be located within an opening either in a fence or a door and through which a hog is adapted to pass and
20 whereby the passing of the hog therethrough will cause the insecticide to be applied automatically on the hog.

A still further object of the invention is to provide an automatic hog oiling device of the above mentioned character, wherein a predetermined amount of disinfectant will by the action of gravity automatically be sprayed or otherwise discharged upon the hog when it passes through the frame supporting the device, the weight of the hog causing the operation and discharge of the disinfectant.

A further object of the invention is to provide an automatic hog oiling device which is simple in construction, inexpensive, strong and durable, and further well adapted for the purposes for which it is designated.

Other objects and advantages of this invention will become apparent during the course of the following description.

In the accompanying drawings, forming a part of this specification, and in which like numerals designate like parts throughout the same,—

45 Figure 1 is a front elevation of my device. Figure 2 is an end elevation thereof, show-

Figure 2 is an end elevation thereof, showing the manner in which the platform is connected to the cylinder actuating means.

Figure 3 is an enlarged longitudinal section of the casing and cylinder mounted therein.

Figure 4 is a transverse section taken on line 4-4 of Fig. 3.

55 In the drawings wherein for the purpose of illustration is shown the preferred embodiment of my invention, the numeral 1 design-

nates generally a frame which is substantially rectangular in design and is adapted to support on the top thereof the reservoir 2 which may be constructed of any suitable metallic material and in which is adapted to be contained the liquid disinfectant or insecticide. This reservoir is so supported on the upper part of the frame 1 as to extend longitudinally over a pair of spaced beams 3 and 4, respectively, as clearly shown in Figure 2 of the drawing. The purpose of this arrangement is to provide a means for enabling the casing 5 which is substantially circular in cross section as clearly shown in Fig. 4 of the drawing, and which is furthermore secured to the bottom face of the reservoir to extend between the spaced beams. 60 65 70

As is clearly shown in Figure 1 of the drawing the cylinder 5 is arranged substantially in the central portion of the bottom of the reservoir and is provided in its upper face with an opening or aperture 6, the latter communicating with a similar aperture 7 provided in the bottom of the reservoir, the purpose of which will hereinafter be more fully described. This casing is open at its respective ends, as clearly shown in Figure 3 of the drawings, and adapted for slidable movement therein is the cylinder 8, the latter being closed at its respective ends, as shown at 9 and 10, respectively, in Figure 3 of the drawings and is also of a length slightly less than the length of the casing.

The cylinder 8 is also provided in its upper portion with an aperture or opening 11 and normally this aperture 11 is adapted to register with the registering apertures 6 and 7, provided in the casing 5 and the reservoir 2, respectively, as heretofore clearly described. 90 95

The cylinder 8 is furthermore provided with an opening 12 which is arranged at a point diametrically opposite the opening 11 and which is normally out of registry with the opening 13 provided in the bottom of the casing 5, the latter opening being arranged substantially adjacent one end of the casing. For the purpose of normally holding the cylinder 8 within the casing 5 in such a position as to enable the cylinder to be filled by the action of gravity with the liquid disinfectant contained within the reservoir 2, whereby a charge of a predetermined amount is discharged into the cylinder, a suitable coil spring such as is shown at 14 in the drawings is connected at its inner end to the end

wall 9 of the cylinder, in any suitable manner, and at its outer end to suitable fastening means extending transversely across the outer ends of the longitudinally extending beams 3 and 4. It is also to be understood that this spring 14 is located between the spaced longitudinal beams 3 and 4, so as to permit the proper functioning of the same, and as is heretofore stated, the beams are so spaced with relation to one another as to permit the casing 5 to fit snugly therebetween, thus permitting the free longitudinal movement of the cylinder 8 when the same is actuated by means hereinafter more fully described.

Pivots supported between the opposite ends of the longitudinal beams 3 and 4 and arranged in the space formed therebetween is the bell crank lever 15. Connected to the shorter arm thereof is the lever 16 which has its inner end threaded into the end wall 10 of the cylinder 8 in the manner as clearly shown in Figure 3 of the drawing. This bell crank lever 15 may be supported on the transversely extending pin 17 in any desired manner and connected to the longer arm of the bell crank lever at its upper end is the elongated arm 18. This arm is also adapted to extend longitudinally in the slotted portion 19 of one of the side beams 20 of the frame 1, and adapted to be connected at its lower end by means of a link 21 to a platform or treadle 22, which is supported on the bottom 23 of the frame 1 by having the inner end thereof provided with an aperture for the purpose of receiving the upstanding bolt 24 which is supported by the base or bottom 23 of the frame, and the aperture may be in the form of an elongated slot so as to permit the vertical movement of the platform on the bolt, as will be presently described.

Normally the outer end of the platform 22 extends upwardly at an angle with respect to the inner end as clearly shown in Figure 1 of the drawings, and the spring 14 normally holds the cylinder 8 within the casing 5, in such a manner as to prevent the charge of disinfectant contained in the cylinder, the latter being fed to the cylinder by the action of gravity, as heretofore described, and thus preventing the accidental loss or dispensing of the disinfectant when the device is not in use. In certain seasons of the year it becomes necessary to treat hogs with a disinfectant whereby the vermin may be exterminated, thus preventing any injury or discomfort to the hogs. By placing the device within an opening provided either in a fence or a door and through which the hogs must pass either in leaving or entering the hog pen, the device is rendered operative and positive in its action so that upon a hog passing through the frame, it will step upon the platform 22

automatically depressing the same and consequently causing the arm 18 to be lowered which will result in the forward movement of the cylinder 8 within the casing 5 against the tension of the coil spring 14 so as to cause the opening 12 provided in the bottom of the cylinder to be brought into registry with the opening 13 provided in the bottom of the casing 5.

This forward movement of the cylinder 75 will simultaneously cause the opening or aperture 11 provided in the top of the cylinder to be brought out of registry with the apertures 6 and 7, thus shutting off the further supply of disinfectant to the cylinder and permitting the charge contained within the cylinder to be dispensed through the registering apertures 12 and 13 by the action of gravity, whereby the disinfectant is sprayed onto portions of the body of the hog. After the hog has stepped off of the platform 22 the spring 14 will automatically return the cylinder 8 to its normal position within the casing 5, whereby the discharge apertures 12 and 13 are moved to an inoperative and non-registering position, and again permitting the aperture 11 to register with the apertures 6 and 7 whereby a further charge of disinfectant may be admitted from the reservoir to the cylinder, thus setting the device in position for use by the next hog to pass through the frame.

It will thus be seen from the foregoing description, that a hog oiling device has been provided which is very simple in construction, entirely automatic in its operation, and one which is furthermore positive in its action and limiting the amount of disinfectant which is sprayed on the hog, thus preventing any waste and assuring an equal discharge of a certain amount of the disinfectant upon each hog.

It is to be further understood that this invention is not alone limited in its use for the treatment of hogs, as any other stock such as fowls, or the like, may also efficiently use the device and control the operation thereof.

The arrangement of the several parts of my invention are such as will enable the same to be readily disassembled whenever desired in order that they may be cleaned and does not necessitate the employment of any complicated means for actuating or setting the same in position for use.

From the foregoing description of the construction of my improved apparatus, it will be seen that I have provided a simple, inexpensive and efficient means for carrying out the objects of the invention, and while I have particularly described the elements best adapted to perform the functions set forth, it is obvious that various changes in form, proportion, and in the minor details of construction may be resorted to, without

departing from the spirit or sacrificing any of the principles of the invention.

Having thus described my invention, what I claim as new and desire to secure by Letters Patent is:—

1. A stock disinfecting device comprising a frame, a reservoir mounted thereon, a cylinder slidably associated with said reservoir and adapted in its normal position to be filled with the disinfectant contained in said reservoir by the action of gravity, means for holding said cylinder in its normal position, and means for discharging the contents of said cylinder by the weight of stock passing through said frame, and including an animal actuated platform pivoted to the lower end of the frame, a bell crank lever pivoted to the upper end of the frame, a rod connected with the bell crank lever and the free end of the platform, and an operative connection between the cylinder and bell crank lever.

2. A stock disinfecting device comprising a frame, a reservoir mounted thereon, a casing associated with the bottom of said reservoir, the casing having an opening in the upper portion thereof communicating with an opening provided in the bottom of said reservoir, a cylinder supported in said casing and adapted for slidale movement therein, said cylinder having an opening in the upper portion thereof communicating with said mentioned openings, whereby the cylinder may be filled with the liquid disinfectant contained in said reservoir by the action of gravity, means for normally holding said cylinder in its filling position, said cylinder having a discharge opening in the

bottom thereof adapted to register with a discharge opening provided in the bottom of said casing upon the forward movement of said cylinder in said casing, means in said frame and connected with said cylinder for moving the same into an operative position upon the passing of stock through said frame, whereby the charge within said cylinder is dispensed through said discharge openings onto said stock by the action of gravity.

3. A stock disinfecting device comprising a frame, a reservoir mounted thereon, a casing carried by the bottom of said reservoir, and having an opening in the top thereof communicating with an opening provided in the bottom of said reservoir, a cylinder slidably supported in said casing and having an opening in the top thereof communicating with said mentioned openings, in its normal position, whereby said cylinder is filled with a disinfectant contained in said reservoir by the action of gravity, said cylinder and casing having discharge openings in the bottom thereof, a platform mounted in the bottom of said frame, means connecting said platform to said cylinder whereby the latter is actuated upon the weight of stock stepping on said platform, so that said discharge openings register with one another to cause the charge of disinfectant contained within said cylinder to be discharged upon said stock by the action of gravity, and means for returning said cylinder to its normal position upon said stock stepping off of said platform.

In testimony whereof I affix my signature.
ORLANDO A. LEMON.
